ARTIFICIAL FISH BAIT

George A. Schmidt, Southfield Township,
Oakland County, Mich.

Application March 30, 1953, Serial No. 24,255

Term of patent 14 years

(Cl. D31—4)

To all whom it may concern:

Be it known that I, George A. Schmidt, a citizen of the United States, residing at Southfield Township, State of Michigan, have invented a new, original, and ornamental Design for an Artificial Fish Bait, of which the following is a specification, reference being had to the accompanying drawing, forming a part hereof.

Fig. 1 is a side elevational view of an artificial fish bait showing my new design;

Fig. 2 is a bottom plan view of the artificial fish bait;

Fig. 3 is a top plan view of the artificial fish bait; and

Fig. 4 is a front elevational view of the artificial fish bait.

The characteristic features of my design reside in the portions shown by means of full lines in the drawing.

I claim:

The ornamental design for an artificial fish bait, as shown and described.

GEORGE A. SCHMIDT.
